UNITED STATES PATENT OFFICE.

WASHINGTON B. VANDERLIP AND CHARLES H. VIGGARS, OF LOS ANGELES, CALIFORNIA.

BRAIN TELEPHONE.

Application filed December 21, 1921. Serial No. 523,869.

To all whom it may concern:

Be it known that we, WASHINGTON B. VANDERLIP, a citizen of the United States, and CHARLES H. VIGGARS, a subject of the King of Great Britain, both residing at Los Angeles, in the county of Los Angeles and State of California, have invented new and useful Improvements in a Brain Telephone, of which the following is a specification.

10 This invention relates to the translation of sound vibrations to the brain of a person without the intervention of the ear.

It has been found, that, if sound vibrations or vibrations of matter corresponding to the 15 sound vibrations are concentrated upon the skull of an individual that these vibrations are translated to the brain and recognized as sounds. By providing proper instrumentalities to take advantage of this physiological fact, it is possible to hear without 20 the aid of the ear, and thereby the deaf may be made to hear sounds. This invention relates to apparatus especially suitable for transmitting vibrations corresponding to 25 sound vibrations to the skull. It is an object of this invention to provide a device of the character described which will be inexpensive, and efficient.

We accomplish this object by means of 30 the embodiment of our invention illustrated in the accompanying drawings, in which:

Fig. 1 is a perspective view of an incomplete band with parts broken away to better illustrate the invention; Fig. 2 is an enlarged view of a detail of the band and an electromagnet mounting; Fig. 3 is a perspective view of the permanent magnet used in a receiver; Fig. 4 is a perspective view of the ring mounting for a receiver unit; and 40 Fig. 5 is a perspective view of a spacing ring.

Referring more particularly to the drawing, 6 indicates a band of thin flexible magnetic metal to girdle the crown of the head of the user. To fasten it in position, a leather strap 7 having a buckle 8 is shown attached to one end, and a strap 9 with holes to be engaged by the buckle tongue is fastened to the other end. The means of securing the band 6 in position upon the head forms no part of our invention, and it is understood that any means conducing to comfort of the wearer may be employed. The band is formed with arms 10, which

may be stamped from the metal sheet and 55 formed integral with the band, and then bent upwardly at right angles to the plane of the band. At the left of Fig. 1, opposing arms 10 are shown before they are bent. These arms are provided with slots 11 to 60 receive bolts. It may be found advantageous to perforate the band between the arms in order to provide a spot more responsive to vibration. To this end we have shown four slits 12. Secured between opposing arms is 65 a ring 14 of diamagnetic material, such as brass or copper. This ring has ears 15 with threaded bores to receive cap screws 16. Extending through the ring are holes 17 to permit the passage of screws 18 for the purpose of securing thereto an arcuate permanent magnet 19. Threaded screw holes are provided in the permanent magnet to engage the screws 18. Clamped between the magnet 19 and the ring 14 are pole pieces 70 20 having extending therefrom at right angles electromagnet cores 21 integral therewith. These cores are for electromagnet windings 22. The cores have their ends close to the band 16, the latter serving as a diaphragm. Fastening the ends of the cores 21 in position is a bridge of diamagnetic material 23. It is obvious that the cores of a receiver may be spaced from the band 6 to give the desired air gap by loosening the screws 80 16 and moving the ring 14 to or from the band 6.

In order to localize the vibrations created in the band 6, contact spacing rings 24 are fitted over the inside of the band. These 90 contact rings come into engagement with the head of the wearer and space the band allowing a freer vibration of the band at each receiver unit. A contact ring is conveniently secured in position by means of 95 ears 25 which register with the arms 10 on the band and have screw slots 26 to permit the passage of the screws 16. It is also understood that these contact rings may be of metal, felt, or any other suitable material. 100

In the device as shown herein, a band has been illustrated with three receiver units. It is understood that a single unit or a multiplicity of units may be mounted upon the band as experiments and the peculiarities of 105 the particular individual indicate, will produce the most efficient results. The receivers may be connected in series or in parallel

2
as desired. The instrument shown is intended to be used with a telephonic transmitter and if desired amplifying devices, which are well known in the telephone art. In such a system the air vibrations are translated into electrical vibrations, which are by means of the receiver translated into mechanical vibrations directly upon the skull of the user of the instrument. As has been before stated these vibrations are conveyed to the brain and the sound is heard.

What we claim is:

1. In a device of the class described, a flexible band constituting a telephonic receiver diaphragm, said band being adapted to embrace the head, and an electromagnet

mounted on said band so as to vibrate said diaphragm.

2. In a device of the class described, a resilient flexible band of magnetic material adapted to embrace the head, and an electromagnet mounted on said band so as to vibrate the latter as a diaphragm.

In witness that I claim the foregoing I have hereunto subscribed my name this 13th day of December, 1921.

CHARLES H. VIGGARS.

In witness that I claim the foregoing I have hereunto subscribed my name this 14th day of December, 1921.

WASHINGTON B. VANDERLIP.
